DESIGN FOR A TRUCK TANK

Ralph B. Ziegler, Philadelphia, Pa., assignor to Quaker City Iron Works, Philadelphia, Pa., a corporation of Pennsylvania

Application March 15, 1940, Serial No. 90,928

Term of patent 7 years

To all whom it may concern:

Be it known that I, Ralph B. Ziegler, a citizen of the United States of America, residing at Philadelphia, in the county of Philadelphia and State of Pennsylvania, have invented a new, original, and ornamental Design for Truck Tank, of which the following is a specification, reference being had to the accompanying drawings forming part thereof.

Fig. 1 is a side elevational view of a truck tank, showing my new design.

Fig. 2 shows the top plan view of the truck tank.

Fig. 3 is a perspective view of the truck tank.

Fig. 4 shows the truck tank in front end elevation; and

Fig. 5 shows the rear end elevation of the same.

I claim:

The ornamental design for a truck tank, as shown.

RALPH B. ZIEGLER.
